UNITED STATES PATENT OFFICE.

JOHN J. GAYNOR, OF INDIANAPOLIS, INDIANA, ASSIGNOR TO THE L. & G. MANUFACTURING CO., OF INDIANAPOLIS, INDIANA, A CORPORATION.

BOTTLE-LABELING MACHINE.

1,174,139.

Specification of Letters Patent. Patented Mar. 7, 1916.

Application filed July 8, 1915. Serial No. 38,698.

To all whom it may concern:

Be it known that I, JOHN J. GAYNOR, a citizen of the United States, residing at Indianapolis, in the county of Marion and State of Indiana, have invented certain new and useful Improvement in Bottle-Labeling Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to bottle labeling machines and has for its object to provide certain improvements in the construction and arrangement of the parts and mechanisms whereby the entire machine is greatly simplified, and all cam mechanisms dispensed with.

With this and other objects in view the invention consists in the novel construction, arrangements and combinations of the labeling mechanism, and particularly in the instrumentalities employed to eliminate the usual cam mechanisms, thus simplifying the entire construction.

The invention also consists in certain other novel features and details of constructions, all of which will be first fully described and afterward specifically pointed out in the appended claims.

Referring to the accompanying drawings Figure 1 is a vertical sectional view through a bottle labeling machine constructed in accordance with this invention illustrating the position of the parts at the time that a bottle to be labeled is being delivered to its receiving means. Fig. 2 is a similar view illustrating the position of the parts at the time that a bottle to be labeled has reached its proper position in the receiving means, and is about to receive its label or labels from the label carrier. Fig. 3 is a similar view illustrating the position of the parts when the bottle has received its label or labels from the label carrier and is about to be passed through the label wipers, and the label carrier is receiving its paste from the paste distributing roll. Fig. 4 is a similar view illustrating the position of the parts when the bottle has been carried through the label wipers with its label or

labels thereon and illustrating also the label carrier in the act of receiving a label from the label box. Fig. 5 is a similar view, illustrating the position of the parts when the bottle is released from its holding mechanism and the label affixing finger to be delivered from the machine, and also illustrating the label carrier with a label thereon for application to the next or succeeding bottle. Fig. 6 is a side elevation of a bottle labeling machine constructed in accordance with this invention taken from the driving side of the machine. Fig. 7 is a front elevation of the machine. Fig. 8 is a horizontal sectional view taken through the machine, the paste box being removed, and Fig. 9 is an elevation of the label carrier.

Like numerals of reference indicate the same parts throughout the several figures in which—

1 indicates the bottle labeling machine which includes suitable vertical frame pieces 2 and horizontal frame pieces 3.

4 indicates the drive pulley which is mounted on a shaft 5 suitably journaled in the machine, said shaft 5 mounting a sprocket 6 chained to a sprocket 7 for driving the paste feed roll 8 which is mounted in a paste box 9, and is in rolling contact with the paste distributing roll 10 which is journaled at 11 and swings on the axis or shaft 12 of the paste feed roll 8, so that the paste distributing roll 10 may have a resilient rolling contact with the label carrier as will be hereinafter described.

The drive shaft 5 is provided with a crank 13 upon which the arm or bar 14 of the label carrier 15 is journaled, the end 16 of the arm 14 being pivoted at 17 to a link 18 which in turn is pivoted at 19 to the frame-work of the machine, said crank 13 also including a relatively long arm 20 which is pivoted at 21 to a link 22 which in turn is pivoted to the arm 23 carrying the label affixing finger 24, said arm 23 having its bottom end pivoted at 25 to the machine. Pivoted to the arm 23 at 26 is an arm 27 which carries at its upper end the bottle engaging and holding element 28 which as shown in the drawings is horizontally recessed at 29 to receive the bottle 30, while a spring 31 is connected to said arm 27 and to the frame of the machine to normally hold said arm in the position shown in Fig. 1. Pivoted to

the arm 23 at 32 is a trip lever 33 notched at 34 for locking engagement with a pin 35 on the spring-held arm 27, while said trip lever 33 is also provided with a similar 5 notch 36 which in connection with the pin 35 acts as a stop to limit the relative movement of the two arms 23 and 27.

Referring now to the paste box 9 it will be seen that the same is removably secured 10 to the shelf 37 by means of screws 38 so as to provide for ready removal of the paste box and rollers for soaking and cleaning, while as will appear from Fig. 7 a clutch 39 is interposed in the paste roller shaft 12, 15 so that a ready disconnection of the paste box and rollers is provided for.

Referring now to the label box or boxes 40 it will be seen that the same are mounted on an arm 41 pivoted at 42 at the top of the 20 machine, a counterpoise 43 being provided for holding the said paste boxes in position shown in Fig. 1. Pivoted to one of the arms 41 for the paste boxes is a link 44 which passes through a guide 45 mounted 25 in the frame of the machine, to the end of which link 44 is adjustably secured a trip element 46 by means of which the label boxes 40 are actuated as will be hereinafter described.

Referring to Fig. 7 it will be seen that 30 each of the label boxes 40 are mounted on two transverse shafts 47 and 48, so as to be capable of a transverse adjustment in order that the positions of the labels to be received 35 by the label carrier can be properly adjusted, so that upon application to the bottle they will be properly positioned thereon.

Referring to Fig. 4 it will be seen that the 40 crank 13 has applied thereon an arm 49 mounting a roller 50 which rotates with the crank 13 in the path of the trip element 46 on the link 44. Mounting as shown in Fig. 4 and as more particularly illustrated in Fig. 8 is the bottle stop mechanism 51 which 45 is pivoted at 52 to an arm or bracket 53 secured to the frame of the machine, said stop mechanism 51 including two vertically depending fingers 54, a central counterpoise 55 and a rearwardly extending trip arm 56, 50 which is in the path of movement of the pin 57 laterally extending from the label carrier arm 14, so that upon movement of the said arm 14 the pin 57 on the downward movement of the arm 14 will engage the trip 55 arm 56 of the bottle stop mechanism 51 and cause same to be rotated on its pivot 42, thus raising the two depending fingers 54 out of engagement with the bottle and allowing said bottle to roll down the incline 58 into position shown in Fig. 1, the 60 said depending fingers 54 being caused to quickly assume their normal position by reason of the counterpoise 55, so as to stop the succeeding bottle on the bottle incline or 65 chute 58. Arranged on the frame of the

machine and in the path of movement of the trip 33 is an adjustable screw 59 for engagement with the depending arm 60 of the trip 33. Arranged vertically of the machine and under the paste box 9 are the label 70 wipers 61 which are preferably of a resilient material such as sheet rubber, so that upon the passage of the bottle therethrough the label or labels will be engaged, wiped and smoothed out on the bottle.

Referring now particularly to Fig. 8 it will be seen that the label affixing finger 24 is pivoted to the arm 23 at 62 so that said finger 24 will have sufficient resiliency to insure its proper functioning upon bottles of 80 varying diameters, a leaf spring 63 being provided to impart to the finger 24 sufficient tension to insure a proper and effective engagement with the bottle. The finger 24 also includes a member 64 pivoted at 65 and 85 held by a spring 63' and having two resilient extensions 66 for immediate engagement with the label or labels in the manner as is clearly shown in Fig. 8.

Having thus fully described the several 90 parts of this invention, its operation is as follows: The bottles to be labeled are placed on the incline or chute 58 and by reason of the stop mechanism 51 the first bottle on the chute or incline 58 is released into position 95 shown in Fig. 1 and drops into position shown in Fig. 2. Referring now to Fig. 3 it will be seen that upon upward movement of the label carrier 15 it comes in contact with the paste distributing roll 10 and receives a proper supply of paste upon the face of the bifurcated label carrier 15, the 100 said carrier then progresses to the label box or boxes 40, and as it reaches the position shown in Fig. 4 the roller 50 comes into contact with the trip element 46 on the link 44, causing the label box or boxes 40 to swing with their arms 41 on the pivot 42, thus causing the label box or boxes 40 to be brought into engagement with the pasted 105 face of the bifurcated label carrier 15 to deposit thereon a label or labels from the boxes 40. As the label carrier 15 and its arm 14 passes into position shown in Fig. 5 with the label or labels on the label carrier 110 the roller 50 releases the trip member 46 and allows the label box or boxes 40 to assume their normal position. As the label carrier 15 and its arm 14 pass downwardly the laterally extending pin 47 on said arm 14 engages the trip arm 56 of the bottle stop mechanism 51 rocking said mechanism on its pivot 115 52 and raising the depending fingers 54 to release the bottle, which is accomplished as the label carrier 15 substantially reaches the position shown in Fig. 1. As the label carrier 15 progresses forwardly into position shown in Fig. 2 the bottle has assumed its proper position in the bottle holder 28. As 120 the label carrier 15 continues to progress 125 130

forwardly the arm 23 with the label affixing finger 24 is caused to move toward the rear of the machine by reason of the link 22, thus causing the label affixing finger 24 to pass through the bifurcated label carrier 15 and engage the label or labels thereon, and bringing the same into contact with the bottle 30 in the manner as shown in Fig. 3. While this is being accomplished the label carrier 15 is passing upwardly to the paste roll 10 as also shown in Fig. 3, while this rearward movement of the arm 23 causes the trip 33 to engage the pin 35 on the arm 27 in the notch 34 of the trip 33 in the manner as shown in Fig. 3, thus locking the two arms 23 and 27 together, and effectually maintaining the bottle 30 between the label affixing finger 24 and the bottle holder 28. The two arms 23 and 27 being thus locked together and engaging the bottle, the link 22 by reason of its crank arm 20 carries the two levers 23 and 27 into position shown in Fig. 4, thus carrying the bottles through the label wipers 61 to wipe and smooth the label or labels on the bottle. As the arms 23 and 27 continue to progress the trip arm 60 of the trip 33 comes into contact with the stop 59 as shown in Fig. 5, which rocks said trip 33 and causes the pin 35 on the arm 27 to be released from the notch 34. When this is accomplished the spring 31 acting on the arm 27 instantly separates the two levers 23 and 27 causing the bottle 30 to be released by the label affixing finger 24 and the bottle holder 28, and deposits the bottle 30 on the delivery chute 59^a in the manner as shown in Fig. 5. This movement of the arm 27 is stopped by the second notch 36 in the trip 33, and upon opposite or rearward movement of the link 22 the arms 23 and 27 are caused to assume their positions shown in Fig. 1, which is the normal position of the arms 23 and 27. These operations are successively continued and are of course duplicated as each bottle is delivered to the bottle holder to be labeled.

Having thus fully described the invention it is of course apparent that the same is susceptible to certain changes in the construction and arrangement of the parts, and I consider myself clearly entitled to all such modifications as fall within the limit and scope of the appended claims.

What I claim as new and desire to secure by Letters Patent of the United States is—

1. A bottle labeling machine, including a bottle holder, means for delivering bottles to be labeled to said bottle holder successively, a label carrier, a bar supporting the same, a crank journaling said bar, a link to which said bar is pivoted, a rotatable drive shaft for rotating said crank to impart to said label carrier a substantially elliptical movement, a label affixing finger, a pivoted arm resiliently mounting said label affixing fin-

ger, means acting on said bottle holder to normally retain the same apart from said label affixing finger, means connecting said drive shaft with the said arm, a trip connection between the said arm and the said bottle holder, said connection between said drive shaft and said arm imparting to said arm a rocking movement causing said label affixing finger to oscillate in substantially a horizontal plane causing said arm and label affixing finger to approach said bottle holder to lock the said arm and said bottle holder together, and to remove a label from said label carrier and affix the same to a bottle, said connection between said drive shaft and the arm of the label affixing finger causing the arm to move said bottle holder, a label wiper arranged in the path of movement of said bottle holder and said label affixing finger to wipe the label, a stop in the path of movement of the said trip on said arm to engage said trip to release said bottle holder to deliver a bottle therefrom, a paste box and a label box to distribute paste and apply a label to the label carrier substantially as described.

2. A bottle labeling machine, including a label carrier, an arm supporting the same, a rotatable crank journaling said arm to impart to said label carrier a substantially elliptical movement, means for distributing paste on said label carrier, a label box for delivering a label to said label carrier, a bottle holder, means for delivering bottles to be labeled successively to said bottle holder, a label affixing finger, means for oscillating the same in substantially a horizontal plane to cause same to pass through said label carrier to remove a label therefrom and to affix a label to a bottle in said bottle holder, means for locking the said label affixing finger in close association with said bottle holder and in close engagement with a bottle therein, a label wiper, said means for oscillating said label affixing finger moving said label affixing finger and said bottle holder through said label wiper and means for effecting a disconnection between said label affixing finger and said bottle holder to release a bottle therefrom.

3. A bottle labeling machine, including a bifurcated label carrier pivotally mounted to move in substantially an elliptical path, a paste distributing roll for applying paste to the label carrier, a label box for depositing a label on the label carrier, a bottle holder, means for delivering bottles successively to said bottle holder, a label affixing finger associated with said bottle holder, means for imparting to said label affixing finger an oscillatory movement simultaneous with the movement of said label carrier to remove a label therefrom and affix same to a bottle, means for locking the said label affixing finger and bottle holder together to

engage and move a bottle and label wiper arranged in the path of movement of said bottle, label affixing finger and bottle holder.

4. A bottle labeling machine, including a label carrier, means for mounting the same and to impart to said label carrier a substantially elliptical movement, means for supplying paste to the label carrier arranged in the path of movement thereof, means for applying a label to said label carrier, a bottle holder, means for delivering bottles successively to said bottle holder, a label affixing finger associated with said bottle holder, and adapted to remove a label from said label carrier and affix same to a bottle, means for moving said label affixing finger and bottle holder and a label wiper arranged in the path of movement thereof.

5. A bottle labeling machine, including a label carrier and means for imparting a substantially elliptical movement thereto, a bottle holder, a label affixing finger associated therewith, means for moving the label affixing finger synchronously with said label carrier to engage and remove a label therefrom to apply same to a bottle, means for locking said label affixing finger and bottle holder together in engagement with a bottle to move the same, a label wiper arranged in the path of movement of said bottle, means for supplying paste to said label carrier, a label box arranged adjacent the path of movement of the said label carrier, means controlled by the movement of said label carrier to move said label box to apply a label on the said label carrier, a bottle holder adapted to receive a bottle to be labeled, a label affixing finger, means for moving the same synchronously with the said label carrier to engage and remove a label therefrom to apply same to a bottle, and a label wiper arranged in the path of movement of said label affixing finger.

6. A bottle labeling machine, including a bifurcated label carrier, a crank actuated arm supporting the carrier to move the same

in an orbit, means for applying paste thereto, a label box mounted adjacent the path of movement of said label carrier, means controlled by the movement of said label carrier for moving said label box to deposit a label on the label carrier, means for removing a label from the label carrier and applying same to a bottle and means for wiping a label so applied.

7. A bottle labeling machine, including a label carrier, a crank actuated arm supporting the carrier to move the same in an orbit, means for applying paste to the label carrier, means for applying the label to the label carrier, a label affixing finger, means for moving the same synchronously with the said label carrier to remove a label therefrom to apply same to a bottle and means for wiping a label so applied.

8. A bottle labeling machine, including a label carrier, a crank actuated arm supporting the carrier to move the same in an orbit, means for applying paste to the label carrier, means for applying a label thereto, a label affixing finger, means for moving the same synchronously with the label carrier to pass said finger through said bifurcated label carrier to remove a label therefrom to apply same to a bottle, and means for wiping a label so applied.

9. A bottle labeling machine, including a label carrier, an arm supporting said carrier to move the same in an orbit, means for applying paste to the label carrier, means for applying a label thereto, a label affixing finger, means for moving the same synchronously with the label carrier to pass said finger through said bifurcated label carrier to remove a label therefrom to apply same to a bottle.

In testimony whereof, I affix my signature, in presence of two witnesses.

JOHN J. GAYNOR.

Witnesses:
